DIRECTIONAL MICROPHONE SYSTEM

Friedrich Spandöck and Erwin Gillitzer, Karlsruhe (Baden), Germany, assignors to Siemens & Halske Aktiengesellschaft, Munich and Berlin, Germany, a German corporation

Application June 6, 1951, Serial No. 230,104

Claims priority, application Germany June 12, 1950

5 Claims. (Cl. 179—1)

This invention is concerned with a directional microphone system especially for use in wireless and in soundfilm work. The invention may be employed in the recording of speech and music or for direct casting over loudspeakers.

The use of directional microphones is broadly known in connection with work which requires correction of spatial conditions that might affect the recording. The recording sensitivity is in such microphones directed upon the scene of recording. Prior proposals suggest to use for such purposes a plurality of microphones arranged in serial relationship to form a receiver group in the manner of a straight radiation group, that is, to form a so-called "microphone line" whose length equals one-half wave length of the lowest frequency which is to be transmitted. The resulting line length was in such arrangements on the order of 1 to 2 m. Such arrangements are cumbersome, and it is often difficult to dispose the microphones without obscuring the viewing field.

Research has revealed that it is important especially in the case of recording in echoing auditoriums and the like to record and to transmit the higher frequencies and that it is in many cases sufficient to employ a high directional adjustment only so far as the higher frequencies are concerned.

The invention proposes for this purpose a directional microphone system in which a plurality of microphones of a receiver group are disposed in a row or line in the manner of a straight radiation group (microphone line) whose length equals at the most one-half wave length of a median frequency of the frequency band that is to be transmitted. The microphone line is disposed vertically or slightly inclined with respect to the scene of recording. The microphones of the line are in such system arranged for cophasal operation and may be connected in parallel, series, or in mixed circuit relationship. The result is a bundling of the directional characteristics in a plane which extends perpendicular to the microphone line. In order to increase the directional characteristics, it will be advantageous if at least some of the microphones of the line exhibit a pronounced directional effect.

If the system comprises, for example, a plurality of microphones of such directional characteristics, the directional effect of the line at low frequencies is given by the characteristics of the individual microphones, while an additional group-directional effect (which finds expression in considerably sharper bundling of the sensitivity characteristics) is obtained for frequencies whose one-half wave length is smaller than the length of the line.

It is in many cases advantageous to use an amplifier which exhibits at least at low and median frequencies an amplification rising with the frequency, because the relatively low directional sharpness at low tones causes preferential direct transmission to the audience of low tones above the echoes of the auditorium so that lower amplification is for such frequencies sufficient.

In the case of a system comprising capacitor micro-

2

phones, the invention proposes to arrange such microphones on the suitably shaped, for example, generally cylindrical or bottle-shaped, pre-amplifier housing or casing. Such casing, together with the microphones carried thereon, is incident to recording suitably so disposed that the microphones are disposed perpendicular or slightly inclined to the scene of recording, and that the sensitivity maxima thereof is trained approximately to the center of the recording scene. By such arrangement is obtained a certain independence of the sensitivity on the distance between the sound source and the microphones, since the sound source with increasing distance from the line is thereby placed in a region of greater directional effect and therewith greater sensitivity.

If a sharper directional effect is also desired for low frequencies, the invention, in accordance with another object, contemplates provision of two microphone lines which are arranged with their longitudinal axes in parallel and in serial relationship relative to the direction of the sound. Each microphone line comprises again a plurality of vertically successively disposed cophasally operating microphones and the two microphone lines are electrically connected in opposition to form a pressure gradient system. The lateral spacing between the two lines is such that the first maximum of the pressure gradient coincides approximately with that frequency at which the group-directional effect of a line becomes effective. The arrangement exhibits good directional effect even at low frequencies, and the sensitivity at such frequencies is by suitable choice of the lateral spacing between the microphone lines sufficient.

In accordance with another feature of the invention, there is provided in serial relationship with one of the two microphone groups or lines a low-pass filter whose upper limit frequency lies in the neighborhood of the first maximum of the pressure gradient. Only one of the two lines is effective above this limit frequency which has, however, a sufficient directional sharpness, due to the group-directional effect, which becomes manifest.

The foregoing objects and other objects and features will appear from a more detailed description of the accompanying drawings, in which:

Figs. 1 and 2 illustrate in diagrammatic manner embodiments in each of which a microphone line is carried by a generally cylindrical or bottle-shaped pre-amplifier casing;

Fig. 3 indicates the manner of interconnecting two microphone lines to form a gradient system; and

Fig. 4 shows diagrammatically an example of two microphone lines each comprising four microphones which may be connected in a circuit as indicated in Fig. 3.

The microphones 1 of Fig. 1 form a line which is so arranged relative to an extension of the pre-amplifier casing 2 that its vertically extending longitudinal axis coincides with the axis of the casing, as is indicated by the dot-dash line 3. The line of microphones is for electrical shielding surrounded by a hood 4 which may be a sound-permeable wire netting or the like placed on the upper end of the casing 2. The current is supplied by way of a cable 5 which also connects the pre-amplifier with the input of the succeeding amplifier.

In Fig. 2 the line comprising the microphone 6 is disposed alongside the pre-amplifier casing 7 in such a manner that its vertically extending longitudinal axis 8 extends in parallel with the casing axis 9. The microphones are again shielded by a suitable sound-permeable hood 10. The current supply and interconnection with the succeeding amplifier are over the cable 11.

The mounting of the microphones of Figs. 1 and 2 may be so constructed and arranged that it remains acoustically ineffective, for example, by the provision of secur-

ing rings which may be thin rods interconnected with each other and with the casing.

The microphones of a line may be arranged upon a small, narrow, elongated soundboard which will advantageously affect the directional operation. Such soundboard, indicated in Figs. 1 and 2 at SB may be included in each example shown.

The interconnection of two microphone lines to form a pressure gradient system is apparent from Fig. 3. The two lines are indicated in the drawing, each by a microphone shown at 12 and 13, respectively. In this schematic representation, the more prominently illustrated electrode denotes the counterelectrodes of the microphones of a line which may, for example, be connected in parallel. The microphones of both lines 12 and 13 lie on their alternating current sides in parallel over the resistor 14, on -A of a control grid of an amplifier tube 15. The grid bias of this tube is produced at the cathode resistor 17 which is bridged by a capacitor 16. The bias for the microphones is obtained from the anode voltage, +A. In the case of the microphones 12 the positive pole of the bias lies on the diaphragms, and in the case of the microphones 13 it lies on the counterelectrode. The direction of the electric field therefore is in the two microphones (lines) opposite and the differential of the microphone voltages thus becomes effective on the grid of the tube 15. This is necessary for obtaining the desired gradient effect. Short-circuiting of the microphone voltage to -A over the resistor 14 is prevented by a capacitor 18. The high-ohmic resistor 19 prevents a shunting of the alternating voltage of the microphones 13 over the net. Between the counterelectrodes of the microphones 13 and the capacitor 18 is disposed a low-pass filter 20 which may, for example, comprise a choke and a resistor parallel thereto. The low-pass filter 20 makes the microphones 13 ineffective for frequencies for which a group-directional effect is obtained in the line represented by the microphone 12.

The entire arrangement therefore operates at low frequencies as a pressure gradient system and at median and high frequencies as a simple line system. The output voltage U is tapped at the anode resistor 21 of the tube 15.

Fig. 4 shows by way of example two microphone lines which may be connected in a circuit as indicated in Fig. 3, each line including four microphones 22-23, respectively. The two lines are so arranged on a horizontally extending pre-amplifier casing 24 that their respective vertically extending longitudinal axes 25-26 are perpendicular to the axis of the casing 24. The directional sensitivity maxima of both lines are such that each line yields a maximum initial voltage responsive to the sound input in the direction of the arrow 28. With identical sensitivity of both lines, there will be obtained, in view of their connection in opposition, a resulting output voltage which corresponds to the pressure gradient between the two line positions. The line 23 has in serial relationship a low-pass filter so that solely the line 22 is effective for the median and the high frequencies.

Changes may be made within the scope and spirit of the accompanying claims.

We claim:

1. A directional microphone system comprising two separate groups of microphones, each group comprising a plurality of individual microphones, means for disposing the microphones of said two groups with their longitudinal axes in parallel, the microphones of each group extending successively along a substantially vertical line

of a length which is at the most equal to one-half wave length of a frequency range which is to be transmitted, circuit means for connecting said microphones in each of said groups for cophasal operation, each group of

5 microphones causing a bundling of the directional characteristics in a plane which extends perpendicular to the plane of the vertical line formed thereby, and means for 10 electrically connecting said microphone groups in opposition to form a pressure gradient system, the spacing between said two groups of microphones being such that the first maximum of the pressure gradient coincides approximately with the frequency at which the group-directional effect of one of said microphone groups becomes effective.

2. A directional microphone system comprising two 15 separate groups of microphones each group comprising a plurality of individual microphones, means for disposing the microphones of said two groups with their longitudinal axes in parallel, the microphones of each group extending successively along a substantially vertical line 20 of a length which is at the most equal to one-half wave length of a frequency range which is to be transmitted, circuit means for connecting said microphones in each of said groups for cophasal operation, each group of microphones causing a bundling of the directional characteristics in a plane which extends perpendicular to the plane of the vertical line formed thereby, means for electrically connecting said microphone groups in opposition to form a pressure gradient system, and a low-pass filter 25 connected serially with one of said microphone groups, the upper limit frequency of said filter being at that frequency at which the group-directional effect of the other group of microphones becomes effective.

3. In the art of recording sound, directional microphone means for receiving said sound, said microphone means comprising a plurality of microphones, amplifier means for amplifying said sound, a casing for said amplifier means, means for securing said microphones on said casing in a generally vertically extending line and spaced from said casing, circuit means for connecting said microphones for cophasal operation, and means forming a directional soundboard for said microphones, said microphones causing a bundling of the directional characteristics in a plane which extends perpendicular to the line formed thereby.

4. The arrangement as defined in claim 3, wherein said soundboard is disposed between said microphones and said casing.

5. The arrangement as defined in claim 3, wherein the length of the line formed by said microphones is substantially equal to one-half wave length of a median frequency of the frequency band to be recorded.
